MORTISE CUTTING DEVICE

Filed Nov. 11, 1927

UNITED STATES PATENT OFFICE

HANS ALMIND, OF NEW YORK, N. Y.

MORTISE-CUTTING DEVICE

Application filed November 11, 1927. Serial No. 232,507.

This invention relates to devices for cutting mortises in the stiles of doors and jambs of door frames and the like for the arranging of hinge butt recesses therein, and it is the primary object of the invention to provide a device of this character which is not only simple in structure but is efficient and practical in operation as well as a labor saving device.

10 A further object of the invention is to combine with a mortise cutting device gauge means to properly position the mortise cut in a door or like stiles and the jamb of a door or like frame to limit the depth of the mortise 15 cut or incision, and also limit the width of the mortise.

Other objects and advantages will herein-after appear.

In carrying out the invention I provide a frame of channel shape and mount cutters within said frame with the cutting edges extended below the bottom edge of the frame, a slicing cutter in the form of a substantially rectangular blade is mounted at the juncture 25 of an end edge with the back edge thereof on one wall of the frame to have movement into and out of the frame, the blade having a cutting edge extending along the longitudinal edge opposite the back edge and the edge at 30 which it is mounted on the frame and arranged with a hand grip to manipulate the same. The frame is arranged with an outward extended flange at the bottom to serve as gauge means to engage with the door stile or frame jamb to limit the depth of the cut of the frame cutters and thereby the depth of the mortise cut or incision, and arranged with gauge means at the outer ends of the frame ends for engagement with the edge of 35 a door or frame to limit the width of the mortise. The end of the wall of the frame opposite to that upon which the slicing cutter is mounted is extended to project outward and inward for the engagement of the slicing cutter as it is moved into the frame to guide the same, said extension of the end wall of the frame and the mounting of said cutter upon the frame being arranged whereby the slicing cutter will be guided in a plane substantially with the cutting edge of the frame

cutters. An adjustable gauge is provided which is adapted to be releasably mounted upon either end wall of the frame to extend outwardly therefrom to co-operate with the top edge of a door or frame to properly position the device and locate the mortise in the door or frame.

In the drawing accompanying and forming a part of this application Figure 1 is a plan view of my improved mortise cutting device showing the same positioned upon the edge of a door, only a portion of which door is shown, preparatory to cutting a mortise therein.

Figure 2 is a side elevation looking at the left of Figure 1, a portion of the slicing cutter being broken away.

Figure 3 is a sectional view, on an enlarged scale, taken on the line 3—3 of Figure 1 looking in the direction of the arrow.

Figure 4 is a perspective view of the cutter carrying frame.

Figure 5 is a perspective view of the cutter mounted on the side wall of the frame;

Figure 6 is a perspective view of one of the cutters mounted on an end wall of the frame.

The embodiment of the invention illustrated in the drawing comprises a frame of channel shape including a side wall 7 and integral right angle end walls 8 and 9. While this frame may be variously constructed as by casting or otherwise, it is preferably stamped from a plate and shaped to form, as by dies, thus greatly facilitating the manufacture of the same. Cutters or blades 10, 11 and 12 are fixed upon the inner surface or within the frame with a portion of the blades extended above the top of the frame, as at 10', 11' and 12', the cutter 12 being secured to the side wall by screws 13, and the end cutters by screws extended through perforations in the end walls and cutters with wing nuts threaded thereon at the outer side of the frame, for a purpose to be hereinafter described, as shown at 14. One edge of the cutters is arranged with a cutting edge 15 to constitute the bottom edge, said cutters being fixed to the frame with the cutting edges extended beyond the bottom edge of the

- frame, as shown at 16 in Figures 2 and 3, and are adapted to make the outline and depth cut or incision of the mortise into a door stile or jamb of a door frame. To facilitate the making of this cut or incision the opposite edges of the cutter 12 are arranged with a cutting edge 17, and the cutters 10 and 11 are arranged with similar cutting edges at the edge adjacent the cutter 12 when mounted on the frame, as shown at 18. To limit the depth cut or incision the frame is arranged with a gauge in the form of a ledge 19 flanged outwardly from the bottom edge of the side and end walls.
- 15 To remove the material within the cut or incision made by the cutters 10, 11 and 12 to form a mortise a slicing cutter is provided, comprising a substantially rectangular blade 20 having a perforated ear 21 extended laterally from the juncture of one end edge with the back edge whereby it is pivotally mounted to have movement into and out of the frame transversely to the cutters fixed to the frame, on a perforated ear 22 extending outwardly and laterally from the end frame wall 8 in a plane with the gauge flange 19, by a screw and nut threaded thereon, as at 23. To arrange the cutter 20 to move in a plane with the cutting edges 15 of the cutters fixed upon the frame, as is shown in Figures 2 and 3, a washer 24 is interposed between the frame and cutter ears 21, 22. The cutter or blade 20 is arranged with a cutting edge 25 to extend along the longitudinal edge opposite the back edge and the end edge at which the adjacent mounting ear 21 is located, as clearly shown in Figure 1. The slicing cutter is also provided with a hand grip to manipulate the same, which may be in the form of a handle 26 fixed to the blade adjacent the back edge to extend opposite to the mounting ear 21.
- To guide the slicing cutter the end wall 9 of the frame is extended to project outwardly and inwardly of the frame, as at 27, this wall being preferably of curved form with the bottom edge 28 extended below the bottom edge of the end wall 9 a distance substantially equal to the portion of the cutting edge of the frame cutters extended below the bottom 45 of the frame and the top edge inclining or converging from the juncture of said wall extension with the end wall to the bottom edge. In the manipulation of the slicing cutter to cut and remove the portion within the depth cutters it is maintained in engagement with the bottom edge of the wall extension 27, this edge being preferably flanged outwardly similar to the frame walls to facilitate the guiding of the gouging cutter. The frame is also arranged with gauge means to limit the width of the mortise. For this purpose a lip 29 is struck downwardly from the frame ear 22, which ear is in alignment with the shoulder formed by the downward extending of the bottom edge of the wall extension 50 55

sion 27, as at 30. In the use of the device it is positioned on a door or frame with the edge shoulder 30 and the lip 29 in engagement with the side of the door stile or door frame. When so positioned a striking member 36 is placed upon the cutter extensions 10', 11' and 12', said member having a central portion 37 adapted to be struck with a hammer or the like to drive the cutters 10, 11 and 12 into the material of the door or frame until the gauge ledge 19 abuts against the door or frame.

To position the mortise relative to the top or bottom edge of a door or frame an adjustable gauge is provided. This gauge comprise plates connected to have longitudinal adjustment, in the present instance shown as two in number 31, 32, said plates being adjustably connected by arranging elongated slots 33 therein for the arrangement of clamping screws 34. One plate, as 31, has one end bent at a right angle and perforated for engagement of either of the screws 14 for mounting the cutters 10 or 11 to mount the gauge upon the frame to extend laterally from either of the end walls 8 or 9. The other plate 32 has the outer end offset at a right angle, as at 35, to engage at the top or bottom edge of the door, this offset portion being of a thickness equal to the clearance desired between the door and door frame and serving as a gauge for this purpose. To assure a severing of the material at the juncture of the end cutters 10, 11 and side cutter 12, or at the corner formed by said cutters, the bottom cutting edge 15 of the cutters 10, 11 at the juncture thereof with side cutting edge 18 of said cutters is extended laterally of the side cutting edge 18 as at 37', this projecting cutting edge also serving to secure the cutters 10, 11 and 12 in incision making position and against displacement as force is applied to the gouging cutter 20 to cut the material between the cutters 10, 11 and 12.

It will be obvious that various modifications may be made in constructions and arrangement of parts without departing from the scope of the invention.

Having thus described my invention I claim:

1. In a mortise cutting device, a frame arranged with a side wall and integral right angle end walls and one end wall arranged at the end with a perforated ear extending laterally in a plane with the bottom edge of the frame and the other end wall extended outward and curved inward, cutters fixed upon the inner surface of the frame walls with the cutting edge extended beyond the bottom edge, a slicing cutter substantially of rectangular form having a cutting edge extended along a longitudinal edge and one end edge thereof with a perforated ear extending laterally from the corner at the juncture of the end having the cutting edge with the back edge of the cutter,

and means to pivotally connect the slicing cutter with the perforated ear of the frame to arrange said cutter to have movement in a direction into and out of the open side of the frame transversely of and in a plane with the cutting edge of the cutters fixed on the frame, and the bottom edge of the outward and inward curved extension of the one end wall of the frame extended below the bottom of the remainder of the frame and adapted for the engaging of the slicing cutter serve as a gauge and guide for the slicing cutter in the cutting operation thereof, and a hand grip fixed to the slicing cutter to extend laterally therefrom opposite to the connection of said cutter with the frame.

2. In a mortise cutting device, a frame of channel shape in longitudinal section, cutters fixed within the frame with the cutting edges extended beyond the bottom edge of the frame, a slicing cutter pivotally mounted on and at the end of one angle wall of the frame to have movement into and out of the open side of the frame transversely of and in a plane with the cutting edge of the cutters fixed in the frame, the angle wall opposite to that to which the slicing cutter is mounted being extended outward and curved inward for the engagement of and guiding of the slicing cutter.

3. In a mortise cutting device as claimed in claim 2, a longitudinally adjustable gauge member adapted for connection with the angle walls of the frame to extend laterally therefrom.

4. A mortise cutting device as claimed in claim 2, wherein the bottom edge of the frame is flanged outward to form an abutment to limit the depth of the mortise cut and the frame walls arranged at the open side of the frame with portions to extend downward beyond the bottom edge thereof to serve as gauges for the width of the mortise.

5. In a mortise cutting device, a frame of channel shape in longitudinal section to constitute a side wall and end walls of the frame, cutter blades of a width greater than the height of the frame, said blades being fixed upon the walls of the frame with the cutting edges extended beyond the bottom of the frame a distance equal to the depth of the cut and extended from the top of the frame to adapt the blades for engagement of a striking member, a slicing cutter substantially of rectangular shape to conform to the space within the frame and having a cutting edge along one side edge and an end edge to adjacent the back edge, said blade having an ear extended therefrom at the juncture of the end cutting edge with the back edge whereby it is pivotally mounted on an end wall of the frame to have movement transversely of the frame and in the plane of the cutting edges of the cutter blades mounted on the frame and in a direction toward and away from the open

side of the frame, and an operating handle fixed to said cutter blade to extend laterally therefrom in the plan of the back edge of the gouging blade and opposite to the pivot ear.

6. A mortise cutting device as claimed in claim 5, wherein the bottom of the frame is flanged outwardly to serve as an abutment to limit the depth of the cut made by the cutters carried upon the sides of the frame, and one wall of the frame having an ear extended laterally therefrom in a plane with the bottom of the frame for the pivotal connection of the ear of the gouging cutter.

7. A mortise cutting device as claimed in claim 5, wherein the end wall opposite to the ear carrying wall is extended outward and curved inwardly to serve as a guide for the gouging cutter during the cutting operation.

Signed at the city of New York, in the county of New York and State of New York this 25th day of October, 1927.
